UNITED STATES PATENT OFFICE.

MILES E. RAY, OF TOLEDO, OHIO, ASSIGNOR OF ONE-HALF TO EDWARD L. FORD, OF SAME PLACE.

HYDROCARBON-BURNER.

SPECIFICATION forming part of Letters Patent No. 472,226, dated April 5, 1892.

Application filed October 19, 1891. Serial No. 409,163. (No model.)

To all whom it may concern:

Be it known that I, MILES E. RAY, of Toledo, county of Lucas, and State of Ohio, have invented certain new and useful Improvements 5 in Hydrocarbon-Burners; and I do hereby declare that the following is a full, clear, and exact description of the invention, which will enable others skilled in the art to which it app pertains to make and use the same, reference 10 being had to the accompanying drawings, and to the figures of reference marked thereon, which form part of this specification.

My invention relates to a hydrocarbon-burner, and has for its object to provide a 15 burner for domestic purposes, wherein there shall be economy of construction, adaptability to stoves of any character, a maximum amount of heat from a minimum supply of 20 hydrocarbon oil, and an entire absence of noise during combustion of the same.

A further object is to provide means for obviating the usual fluctuation in the supply of gaseous fuel to the burner-pipe by arranging supplemental reservoirs for a supply of 25 the gaseous fuel in communication with the burner-pipe, whereby a uniform pressure may be maintained.

The invention consists in the parts and combination of parts hereinafter described, and 30 pointed out in the claim.

In the drawings, Figure 1 is a side elevation of a complete burner. Fig. 2 is a longitudinal vertical sectional view. Fig. 3 is a top plan view with the deflector removed. 35 Fig. 4 is a transverse section on lines x x , Fig. 1.

Heretofore in the branch of the art to which my invention belongs there has been a varying or fluctuating of feed the vapor fuel to the 40 burner, due to an intermittent feed of oil to the vaporizer. It is the object of my invention to obviate this difficulty by providing reservoirs for the vapor fuel, whereby there is insured an even supply of the same to the 45 burner. There has also been an annoying noise during combustion, due to an absence of equilibrium between the escape of the products of combustion and the supply of air to the combustion-chamber. This objection is 50 entirely overcome by my arrangement of air-ports, whereby the air is received both above

and below the burner-pipe, and by an adaptability of adjustment of the deflector-plate, whereby the escape of the products of combustion is equalized with relation to the air- 55 bustion and the supply of fuel to the burner-pipe.

1 designates a shell, preferably comprising a bottom and sides formed integral, with the sides inclining outwardly from the bottom, 60 there being projections 2 on each end, perforated to receive rods 3, screw-threaded upon their upper ends and provided with nuts 4 to adjustably sustain a deflector-plate 5, formed with depending flanges 6 at each end to deflect the products of combustion from impinging upon the sides of the stove in which the shell is placed.

Within shell 1 is arranged a coil of pipe 7, leading from a source of supply of oil to a 70 burner-pipe 8 of T shape, arranged centrally of the shell and having orifices 9, through which the gaseous vapor escapes and is lighted, there being air-ports 10 formed in the shell, extending above and below pipe 8, whereby 75 air is admitted around the burner-pipe in direct alignment with the orifices at which combustion takes place.

At the outer ends of pipe 8 are secured reservoirs 11, which extend vertically from the 80 pipe to avoid an accumulation of any tarry or unvaporized matter, which are designed to receive and store a quantity of the fuel vapor with sufficient pressure to cause the same to flow to orifices 9 should the feed of oil diminish or cease in its flow, whereby there is 85 maintained an even feed at the burner-orifices.

In operation, to start an initial fire, cock 12 is opened to allow oil to flow through the coil 90 and out of orifices 9 into the bottom of the shell when it is lighted, and cock 12 being closed the oil in the coil is quickly vaporized, causing the vapor to issue through the orifices, where it is lighted, and the products of combustion rising heat the coil sufficiently to allow of opening the cock 12 and admitting a constant feed of oil to the burner. Deflector plate 5 is now adjusted to the proper height 95 by screwing nuts 4 either up or down until the plate is the proper distance from the top of the shell to allow the products of combus- 100

tion to escape with a volume coincident with the feed of oil and air and without the disagreeable noise usual in burners of this character. As soon as the vaporizing-coil has 5 become sufficiently heated to vaporize the oil the vapor passes to the orifices and into the reservoirs 11, where a quantity is always present to supply the demand at the burner-orifices should the flow of oil cease or diminish, 10 thereby preventing fluctuation of the flame. I may also construct the shell and vaporizing-coil in circular form, to adapt the same to the combustion-chamber of circular stoves.

What I claim is—

15 In a hydrocarbon-burner, a shell comprising

ing a bottom and sides, an adjustable deflecting-plate supported above the same, a vaporizing-pipe within the shell, a horizontal burner-pipe connected with the vaporizing-pipe, formed with jet-orifices, and openings in the 20 shell coincident with the jet-orifices of an area to admit air both above and below the burner-pipe.

In testimony that I claim the foregoing as my own I affix my signature in presence of 25 two witnesses.

MILES E. RAY.
